UNITED STATES PATENT OFFICE

WOLFRID AALTONEN, OF JERSEY CITY, NEW JERSEY

LOCK

Application filed November 15, 1930. Serial No. 496,011.

This invention relates to improvements in locks, and more particularly to key actuated locks.

The primary object of the invention is to provide a novel lock which cannot be opened although the correct key is inserted therein, unless the operator is familiar with the workings thereof, as it is necessary that the key be pulled outward after insertion and turning in order to release the bolt from its keeper. Thus it will be found difficult for an unauthorized person to successfully actuate the lock even though in possession of the correct key.

Another object of the invention resides in a key actuated lock of the padlock type in which the shackle is locked by one end of a slideable bolt, the latter being constructed to enable the key to be inserted therein lengthwise thereof and turned to release the bolt locking means, after which the key is pulled outward to move the bolt to retracted position free of the shackle.

With these and other objects in view, the invention resides in the certain novel construction, combination and arrangement of parts, the essential features of which are herein fully described, are particularly pointed out in the appended claim, and are illustrated in the accompanying drawings, in which,

Figure 1 is a side elevational view of my improved lock,

Figure 2 is an end view thereof,

Figure 3 is a side elevational view with the cover plate removed,

Figure 4 is a vertical transverse sectional view,

Figure 5 is a view similar to Figure 3, but showing the key in an inserted position within the lock,

Figure 6 is a vertical transverse sectional view on the line 6—6 of Figure 5,

Figure 7 is a vertical transverse sectional view through the lock but showing the key in dog actuating position, and;

Figure 8 is a vertical longitudinal sectional view on the line 8—8 of Figure 7.

Referring to the drawings by reference characters, the numeral 10 designates a cas-

ing or housing which is shown as substantially rectangular in configuration and which is open at one side, the said open side being closed by a cover plate 11 which is secured in position by screws, rivets or like fastening elements 12. Spaced transversely disposed partitions 13 and 14 are mounted within the casing adjacent the opposite ends thereof, and pivoted to an ear extending from the partition 14 is a shackle 15, the same being substantially inverted U-shape in configuration. The free ends of the shackle extend through an opening 16 provided in the top of the casing and has a keeper opening 17 provided therein and which is adapted to register with an opening 18 in the partition 13 when the shackle is in closed position.

Slidably supported by the partitions 13 and 14, is a lock bolt 19, one end of which is reduced to provide a bolt head 20 which is movable through the opening 18 in the partition 13 and into a bolt opening or slot 17 when the bolt is in an extended or locked position.

The bolt 19 is of substantially cylindrical shape and is provided with a key hole shaped slot 21 extending inwardly from one end thereof, while one end of the casing 10 is provided with a similar key hole opening or slot 22 which is in alignment with the slot 21 in the bolt to facilitate the insertion of the stem or shank 23 of a key 24, the said key being provided with a manipulating head or bow 25.

The lock bolt 19 is slidably supported within the casing but is non-rotatable with respect thereto and has its outer periphery provided with grooves or notches 26 at the top thereof. Pivoted to the casing in spaced relation are dogs 27, adapted to seat in the respective grooves or notches 26 when the lock bolt is in extended position and which bolt is normally held in such position by a contractile spring 28, one end of the spring being connected to the bolt and the opposite end to the partition 13. Flat springs 29 supported within the casing bear against the respective dogs 27 and tend to seat them in the respective notches but the bills of the dogs extend slightly beyond the peripheral wall of the

lock bolt as best seen in Figure 4 for a purpose to be presently explained.

In the drawings I have illustrated the lock bolt as being provided with three of the 5 grooves or notches 26 and between the center notch and the notches disposed on opposite sides thereof, the body of the bolt is slotted as at 30, the said slots being divided by transversely disposed webs or flanges 31.

10 The stem 23 of the key 24 is provided with a bit made up of a central U-shaped finger 32, and oppositely disposed L-shaped fingers 33, the latter extending in opposite direction.

15 The fingers 32 and 33 are movable in the slots 30 and the said fingers are spaced so that the webs or flanges 31 will be disposed between the fingers when the key is in a turned position as shown in Figure 8 of the drawings. Assume that the parts of the lock

20 are in the position shown in Figures 3 and 4 of the drawings, the bolt head 20 is in locking engagement with the shackle 15, whereupon the shackle is prevented from being swung to an open position. In order to actuate the bolt 19 to move the same to a retracted or unlocked position, it is necessary to insert the key 24 into the lock through

25 the alined key hole openings 21 and 22, or to the position shown in Figures 5 and 6. When the key is in the position just mentioned, the fingers 32 and 33 are in the path of the free ends of the dogs 27 and by imparting an approximate one half turn to the key, the dogs are lifted from the notches 30 or grooves 26 to the position shown in Figures 7 and 8 of the drawings; it will be remembered that the spring 28 is acting upon the bolt 19 to hold the same in an extended position and although the dogs have been

35 released, the bolt is still in locked or extended position. In order to actuate the bolt 19 to a retracted position, the operator pulls outward upon the key 24, causing the sides of the fingers 32 and 33 to engage the flanges

40 or webs 31 and certain walls of the slots 30 so that the outward pressure will cause the bolt 19 to slide to a retracted position, whereupon the shackle 15 may be swung open to the position shown in dot and dash lines

45 in Figure 8. Upon the outward pull upon the key, the spring 28 will promptly return the bolt to extended position and in which position the shackle may be swung to a locked position so that the bolt head 20 will snap

50 into the bolt slot 17. To again set the lock, the key 24 is turned to bring the fingers 32 and 33 in register with the key hole slot and in so doing the springs 29 automatically seat the dogs 27 in their respective notches,

55 thus locking the bolt against sliding movement in either direction. After the key has been turned to unlocking position, it may be withdrawn from the lock in the usual manner. It might be stated that the opposite

60 65 end walls of the slots 30 constitute stops for limiting the turning movement of the key in opposite direction as the fingers 32 and 33 strike the walls of the slots to permit of only a limited turning movement when actuating the key for unlocking position.

70 From the foregoing description, it will be seen that although a person may be in possession of the correct key for actuating the lock he or she is prevented from doing so unless familiar with the working of the lock as it is necessary to pull outward upon the key after the same has been inserted and turned to a position to release the locking dogs or catches 27.

75 While I have shown and described what I deem to be the most desirable embodiment of my invention, it will be understood that various changes in construction may be resorted to if desired and I do not limit myself to the exact structural details herein set forth nor to anything less than the whole of my invention limited only by the appended claim.

80 Having thus described the invention, what is claimed as new and what it is desired to secure by Letters Patent of the United States, is:

85 A lock comprising a casing, a bolt slidably arranged in said casing and having a plurality of transverse grooves in the top part, a plurality of spring pressed dogs in the top part of the casing engaging the grooves, said bolt having a plurality of transverse slots therein for receiving key parts which move the dog to releasing position and the bolt having a key receiving slot therein which intersects the slots, portions of the walls of the slots acting as abutments for the key parts whereby the bolt can be moved rearwardly by the key and a spring for normally holding the bolt in projected position.

90 In testimony whereof I affix my signature.
WOLFRID AALTONEN.
